UNITED STATES PATENT OFFICE.

JOHN V. CUNNIFF, OF FALL RIVER, AND EDWARD A. CUNNIFF, OF NEW BEDFORD, MASSACHUSETTS.

DESIGN FOR A CHATELAINE-BAG.

43,670.

Specification for Design.

Patented Mar. 4, 1913.

Application filed November 20, 1912. Serial No. 732,600. Term of patent 3½ years.

To all whom it may concern:

Be it known that we, JOHN V. CUNNIFF and EDWARD A. CUNNIFF, residing, respectively, at Fall River, in the county of Bristol and Commonwealth of Massachusetts, and New Bedford, in the county of Bristol and Commonwealth of Massachusetts, have invented a new, original, and ornamental Design for Chatelaine-Bags, of which the following is a specification, reference being had to the accompanying drawing, forming a part thereof.

The figure is a plan view of a chatelaine bag, showing our new design.

We claim:

The ornamental design for a chatelaine bag, as shown.

JOHN V. CUNNIFF.
EDWARD A. CUNNIFF.

Witnesses:

JOHN E. HEALY,
ABBY I. HEALY.
